Fig. 1 is a front elevational view of an atomizing spray dispenser for deodorants or the like embodying our new design;

Fig. 2 is a right side elevational view thereof;

Fig. 3 is a rear elevational view thereof;

Fig. 4 is a top plan view thereof;

Fig. 5 is a front perspective view taken from the top and left side thereof; and

Fig. 6 is an enlarged vertical cross-sectional view thereof taken parallel to the depression of the cap portion and passing through the center of said portion, the bottom of the dispenser being broken off for convenience of illustration.

The dominant features of our design reside in the portions shown in full lines.

We claim:

The ornamental design for an atomizing spray dispenser for deodorants or the like, as shown and described.
